UNITED STATES PATENT OFFICE.

HENRY B. COOLEY, OF NEW BRITAIN, CONNECTICUT, ASSIGNEE TO THE AMERICAN PAPER GOODS COMPANY, OF KENSINGTON, CONNECTICUT, A CORPORATION OF NEW JERSEY.

FLAT-BED ROTARY PRINTING-PRESS.

1,076,004.

Specification of Letters Patent.

Patented Oct. 14, 1913.

Original application filed January 25, 1910, Serial No. 539,942. Divided and this application filed November 11, 1910. Serial No. 591,858.

To all whom it may concern:

Be it known that I, HENRY B. COOLEY, a citizen of the United States, and resident of New Britain, in the county of Hartford and State of Connecticut, have invented a new and useful Improvement in Flat-Bed Rotary Printing-Presses, of which the following is a specification.

My invention relates to a flat bed rotary printing press and more particularly to anti-smutting mechanism for such press, with the object in view of providing effective means for automatically shifting the impressing cylinder bodily away from the form cylinder whenever one or more of several impression segments are not in use, and whenever a paper carrying segment on the impression cylinder fails to receive a paper to be printed.

In the accompanying drawings, Figure 1 is a view of the press in rear elevation. Fig. 2 is a view in end elevation. Fig. 3 is a vertical central section from front to rear. Fig. 4 is an enlarged top plan view of the impression cylinder and its accessories. Fig. 5 is a view of the same in end elevation. Fig. 6 is a detail elevation partly in section. Fig. 7 is a section of the same taken in the plane of the line A—A of Fig. 4. Fig. 8 is a view in detail showing the vibrating arm which supports the electro-magnet for controlling the position of the impression cylinder with respect to the form cylinder and the cam for operating the arm, and Fig. 9 is a view in detail showing the arrangement of the contact plates for maintaining the electric circuit closed when the impression cylinder is not carrying paper to be printed.

The present application is a division of my pending application Serial No. 539,942, filed January 25, 1910.

The frame of the machine is denoted by 1. The drive shaft, denoted by 2, is provided with fast and loose pulleys 3 and 4, which receive power from a suitable source not shown. The drive shaft 2 also carries a balance wheel 5. The shaft on which the form cylinder is carried is denoted by 6. It is provided with a spur wheel 8,

through which the shaft receives motion by means of a pinion 7 on the drive shaft 2.

The impression cylinder is here shown as provided with two oppositely disposed impression segments, denoted respectively by 9 and 10. These segments are mounted in suitable end frames 11 carried by a shaft 12. The latter is mounted in eccentric bearings as will hereinafter particularly appear. The relation of the segments 9 and 10 to the form cylinder is such that they will normally travel along the type beds of the form cylinder with their curved surfaces sufficiently close to the said beds to press the paper carried by them into printing contact with the type held on said beds. These segments 9 and 10 are quite similar in construction and are provided with suitable grippers and blankets, the particular construction of which is not recited here as they form no part of the present invention. The shaft 12 is driven by suitable gearing from the form cylinder shaft, the particular structure of this gearing forming no part of my present invention.

To prevent the face of an impression segment of the impression cylinder from engaging the face of the type on the form cylinder when, either from intention any impression segment is not provided with a sheet to be printed, or, unintentionally a sheet fails to be fed in position, the shaft of the impression cylinder and hence the impression cylinder itself is automatically moved bodily away from the face of the type and held away during the time the face of the impression segment is traveling over the face of the type. This is accomplished as follows: The impression cylinder shaft 12 is mounted eccentrically in bearings one of which is shown at 13, Fig. 5, it being understood that a similar bearing is provided for the shaft 12 at the opposite side of the frame. The bearing 13 and its companion are in turn rotatably mounted in suitable bearings in the supporting frame. Pitmen 14 and 15 are jointed respectively to split collars 16 clamped on the bearing 13 and its companion the said pitmen being engaged

at their opposite ends by cams 17, 18 on the cam shaft 19, the latter being driven from the drive shaft 2 through suitable gears connecting it with the drive shaft. A spring 5 tends to draw the rollers 21, 22, on the pitmen into engagement with the cams 17, 18, lowering the pitmen and hence rocking the bearing 13 and its companion and thereby moving the shaft 12 sufficiently to prevent the face of an impression segment from touching the face of the type. The pitmen 14, 15, are held from unintentional dropping by stop blocks 23, adjustably attached to the pitmen by means, for example, of an elongated slot and set screw 24, 25, which stop blocks rest on a shoulder 26 on a slide 27 supported in a way 28 secured to the frame, the slide being provided with a pin 29 against which the end of a slide operating arm 30 bears.

It is to be understood that there are two slides similarly constructed and arranged, one for each stop block, and that there are two slide operating arms connected by a bottom element 31, forming a general U-shaped structure pivotally secured to the outer sides of the frame 1, one of the pivots being shown at 32. The element 31 is provided with an armature 33 which co-operates with an electro-magnet 34 carried by the lower end of a vibrating arm 35 pivoted to the frame at 36 and connected by a pitman 37 with the shaft 19 on which the forked end of the pitman rides. The pitman 37 is provided with a roller 38 in position to engage a cam 39 similar to the cam 17, to rock the arm 35 against the tension of its retracting spring 40. The slides are moved by springs, one 41 being shown in Fig. 5, into position to arrest the stop block 23 and its companion, thereby holding the pitmen 14, 15, suspended and the impression cylinder in printing position. The parts will remain in this position so long as the electro-magnet 34 remains de-energized, the latter swinging back and forth as the arm 35 is swung during the revolution of the shaft 19, without effect upon the element 31 and its arms. When, however, the electro-magnet 50 34 is energized, it will attract the armature 33 and hence cause the element 31 and its arms to swing in a direction to move the slides against the tension of the spring 41 and its companion, thereby dislodging the stop blocks from the slides, allowing the pitmen 14, 15, to drop and thereby throw the impression cylinder out of touch with the type. Once having dropped, the pitmen 14, 15, will remain down until their operating cams 17, 18, again lift them and thereby rock the impression segment into printing position as it approaches its sheet receiving position.

The energizing and de-energizing of the electromagnet 34 is accomplished as follows: 65 An electric circuit is formed by wires 42, 43, leading from the opposite poles of a battery 44 to binding posts 45, 46, on a projection of the frame 1. Curved contact strips 47, 48, are carried by an end frame of the impression cylinder, a pair of these strips for each impression section of the cylinder, in position to contact respectively with the binding posts 45, 46, before the face of the impression section passes along over the type. 70 These contact strips or plates are connected with contact terminals 49, 50, exposed on the face of the impression section and at all other points suitably insulated from the cylinder. The construction here shown is insulated wires 51, 52, leading from the strips 47, 48, through rubber plugs 53, set in the cylinder. A bridge piece 54 of suitable conducting material, as, for example, brass, is pivoted to a bracket 55 secured to and insulated from the advance edge of the impression section in position for the branches of its forked end to swing into and out of contact with the terminals 49, 50, at the face of the impression section. A spring 56 80 tends to hold the bridge piece out of contact with the terminals. The bridge piece is forced into contact with the terminals to complete the electric circuit through the strips 47, 48, and binding posts 45, 46, by a 85 dog 57 consisting in the present instance of a flat piece of steel having its end split to form branches 58, 59, and secured to an arm 60 attached to an insulating block 61, fixed on a rock shaft 62 mounted in the end frames 100 of the cylinder and provided at one end with a crank 63, the pin on which is provided with a roller in position to engage a cam 64 fixed to the frame 1 and so shaped as to rock the dog 57 and hold it out of position to 105 press the bridge piece 54 into contact with the terminals 49, 50, during the interval when the impression segment is traveling intermediate of successive sheet receiving positions, but permitting the dog 57 to be 110 rocked by its actuating spring 65 attached to an arm 66 on its shaft, just after the impression segment has reached its position to receive a sheet to be printed, in a direction 115 to press the branches of the bridge piece into contact with the terminals 49, 50, thereby completing the circuit through the strips 47, 48 and electromagnet 34 and causing the shaft of the impression cylinder and hence the impression cylinder to be moved away 120 from the face of the type before the impression face of the cylinder reaches the type. The split end of the dog 57 insures the pressure of the branches of the bridge piece into close contact with their respective terminals. 125 The location of the terminals and the

bridge piece is such that when a sheet of paper is fed into position on an impression segment, it will cover the terminals 49, 50, before the bridge piece is pressed down toward them and hence will insulate them from the bridge piece so that the electromagnet 34 will not be energized excepting when no sheet is supplied to the impression section. Hence, so long as the sheets are fed properly to the impression sections, the impression cylinder will remain in position to engage the type but whenever an impression cylinder fails to receive a sheet that impression section will not engage the type and hence its blanket will not become daubed or snuttied.

The relation of the driving and driven gear is such that the rocking of the bearings carrying the impression cylinder shaft may take place, if permitted to rock, just before an impression section begins its travel over a type form and the cams 17 and 39 on the cam shaft serve to operate the respective pitmen 14 and 37 into position, the one to receive the stop blocks on the slides for holding the pitmen 14, 15, suspended and the other to swing the electric magnet into position to attract the arms which move the slides from under the stop blocks and permit the pitmen 14, 15, to drop.

What I claim is:

1. In a printing press, a form cylinder provided with a plurality of type receiving positions, an impression cylinder provided with a plurality of impression segments for carrying sheets to be printed in engagement with the type on the form cylinder, mechanism for bodily moving the impression cylinder toward and away from the form cylinder at the moment one of the impression segments approaches the form cylinder, an electric circuit including an electro-magnet for controlling the said mechanism, and sets of circuit makers and breakers one set for each impression segment of the impression cylinder, one of said circuit makers and breakers of each set being under the control of a sheet to be printed and the other circuit maker and breaker of each set being arranged to determine the length of time the circuit shall be closed whereby the impression cylinder is moved bodily away from the form cylinder whenever an impression segment approaches the form cylinder without a sheet thereon.

2. In a printing press, a form cylinder for receiving the type, an impression cylinder for carrying a sheet into engagement with the type, mechanism for moving the impression cylinder toward and away from the form cylinder, an electric circuit including an electro-magnet for controlling said mechanism, and an extended contact piece carried by the impression cylinder and electrically connected with said terminals and with a pair of stationary terminals in position to be engaged by the said extended contact piece, a spring actuated bridge piece insulated from and carried by the impression cylinder in position to be forced into contact with the aforesaid extended contact piece when

including a circuit maker and breaker consisting of a spring actuated bridge piece 65 pivoted to and insulated from the impression cylinder and means for forcing the bridge piece into position to close the circuit comprising a spring actuated rocking dog insulated from and carried by the impression 70 cylinder and a cam for operating the said rocking dog against the tension of its actuating spring.

3. In a printing press, a form cylinder for receiving the type, an impression cylinder 75 for carrying a sheet into engagement with the type, mechanism for moving the impression cylinder toward and away from the form cylinder, and an electric circuit including an electro-magnet for controlling said 80 mechanism, the said electric circuit also including a circuit maker and breaker consisting of a spring actuated forked bridge piece pivoted to and insulated from the impression cylinder, and means for forcing the 85 bridge piece into position to close the circuit comprising a spring actuated rocking dog insulated from and carried by the impression cylinder and a cam for operating the said rocking dog against the tension of 90 its spring.

4. In a printing press, a form cylinder for receiving the type, an impression cylinder, 95 for carrying a sheet into engagement with the type, mechanism for moving the impression cylinder toward and away from the form cylinder and an electric circuit including an electro-magnet for controlling said mechanism, the said electric circuit also including a circuit maker and breaker consisting of a spring actuated bridge piece pivoted to and insulated from the impression cylinder and means for forcing the bridge piece into position to close the circuit comprising a spring actuated bifurcated dog 100 insulated from and carried by the impression cylinder and a cam for operating the said dog against the tension of its actuating spring.

5. In a printing press, a form cylinder for receiving the type, an impression cylinder 110 for carrying a sheet into engagement with the type, mechanism for moving the impression cylinder toward and away from the type, an electric circuit including an electro-magnet for controlling said mechanism, the 115 said electric circuit being provided with exposed terminals at the surface of the impression cylinder, extended contact pieces carried by the impression cylinder and electrically connected with said terminals and with a 120 pair of stationary terminals in position to be engaged by the said extended contact pieces, a spring actuated bridge piece insulated from and carried by the impression cylinder in position to be forced into contact 125 with the aforesaid exposed terminals when

ever a sheet to be printed fails to enter between the said bridge piece and terminals and means for forcing the bridge piece toward the said exposed terminals as the impression portion of the impression cylinder approaches the type on the form cylinder.

5 In testimony, that I claim the foregoing

as my invention, I have signed my name in presence of two witnesses, this eighth day of November 1910.

HENRY B. COOLEY.
